UNITED STATES PATENT OFFICE.

FRANK JOHNSON, OF GLENDALE, CALIFORNIA.

TOOL.

1,113,788.

Specification of Letters Patent. Patented Oct. 13, 1914.

Application filed December 22, 1913. Serial No. 808,119.

To all whom it may concern:

Be it known that I, FRANK JOHNSON, a citizen of the United States, residing at Glendale, in the county of Los Angeles, State of California, have invented new and useful Improvements in Tools, of which the following is a specification.

This invention relates to a tool, and particularly pertains to a tool for assisting in the insertion and removal of the intake and exhaust valves of gas engines.

It is the object of this invention to provide a tool of the above character by means of which the valve springs of the ordinary intake and exhaust valves of gas engines may be compressed, so as to permit the ready removal of the spring engaging pin from the valve stem to facilitate the removal of the valve; and which may also be employed in putting the valve in place.

A further object of the invention is to provide a valve spring lifter in which the lifting of the spring is effected by leverage and which is so constructed that the fulcrum point of the lifter may be varied to suit changing conditions.

Another object is to provide a device for compressing the valve springs by means of which the springs can be readily engaged and compressed without exerting strains on the valve stem so as to avoid bending of the latter.

Another object is to provide an adjustable support for the tool coöperating with the tool in performing its functions, which support is adapted to be connected with various parts of the engine casing or other rigid structure to suspend the tool.

The invention primarily resides in a shank having a slotted end portion on which a spring engaging disk is pivotally mounted, said disk being slotted to receive the valve stem, and a flexible support adjustably engageable with the slotted end of the shank, substantially as illustrated in the accompanying drawings, in which:

Figure 1 is a perspective view of the invention. Fig. 2 is a detail section in elevation on the line 2—2 of Fig. 1. Fig. 3 is a section and elevation on the line 3—3 of Fig. 2, as seen in the direction of the arrows. Fig. 4 is a side elevation illustrating the application of the invention.

In inserting and removing the ordinary intake and exhaust valves of gas engines, considerable difficulty is met in providing

an effective means for compressing the valve spring and retaining it in a compressed state while inserting the spring supporting pin in the stem, or removing it therefrom. Such tools as have been provided for this purpose are frequently objectionable in that they tend to bend and injure the valve stem thereby hindering the proper operation of the valve. This, and other objectionable features of tools of this class are overcome by the device shown in the drawings, wherein 5 indicates the shank or handle portion of the tool, which shank constitutes a lever and carries a valve spring 70 engaging member, and is designed to be fulcrumed at various points throughout its length. The lever-shank is formed with a yoke 6 on its outer end in which the spring engaging member is mounted, this member comprising a disk 7 having a flange 8 pivotally connected at 9 to the yoke 6, so as to permit of a rocking or swinging movement of the disk in relation to the shank. The flange 8 extends approximately half way 80 around the periphery of the disk 7 and projects upward from its rear edge.

Formed in the disk 7 and in alinement with the shank 5 is an open-ended slot 10, which intersects a central opening 11 in the 85 disk. This slot 10 is provided for the purpose of permitting the disk 7 being inserted beneath the washer 12, and alongside the spring engaging pin 13 on the valve stem 14 so as to position the washer 12 on the upper 90 face of the disk 7 with the valve stem extending centrally of the disk 7 through the opening 11.

Formed in the shank 5 at the base of the yoke 6 is a longitudinally extending slot 15 95 which is open at its outer end to permit the insertion in the slot of the links of a chain 16, which links are constructed with a narrow lower portion 17 of less width than the slot 15 and an enlarged upper portion 18 of 100 greater width than the slot, so that when a link is inserted edgewise in the slot the upper end of the link immediately therebeneath will engage the underside of the shank 5 on opposite sides of the slot as shown in Fig. 3, and extend into opposite grooves or notches 19 on the underside of the shank to form a fulcrum for the shank 5, as will be later described. A series of the notches 19 is provided throughout the length of the 110 slot 15 to permit of adjustment of the fulcrum to different points. The chain 16 is

designed to be secured to a rigid portion of the engine casing 20 and is provided with a hook 21 or other suitable device for that purpose.

5 In the operation of the invention when it is desired to remove a valve the chain 16 is suspended from a rigid portion of the engine casing 20 by means of the hook 21 or otherwise, at a point adjacent the valve 10 stem 14 and in such position as to parallel the latter. The shank 5 is positioned on the chain with opposite notches 19 in engagement with a link thereof at a point slightly above the washer 12, the link being engaged 15 in opposite notches 19 at a point on the shank, according to the distance the chain is spaced from the valve stem and according to the leverage desired. It is desirable that the chain extend parallel with the valve 20 stem, so that a nearly direct upward movement of the inner end of the tool will be effected when the shank is rocked. The disk 7 is then placed below the washer 12 as 25 shown in Fig. 4. The washer 12 will then be arranged above the disk 7 and will abut against the flange 8 which flange will operate to engage the edge of the washer and thereby dispose the disk 7 so that the valve stem 14 will extend centrally of the opening 30 11 clear of the margin thereof. By manually depressing the outer end of the shank 15 to rock the latter into the position indicated in dotted lines in Fig. 4, the disk 7 will be elevated so as to raise the washer 35 12 and cause the spring 23 bearing between the washer 12 and the engine casing 20 to be compressed. The pin 13 can then be readily withdrawn, after which the spring 23 may be gradually relaxed and removed, 40 if desired.

As a means for permitting the disk being readily advanced beneath the ring 12, a groove 24 is formed on its underside in alignment with the slot 10, so that the rear portion of the disk will clear the end of the 45 pin 13.

By pivotally mounting the spring engaging seat or disk 7, the latter will maintain a horizontal position during the arcual movement of the yoked end of the shank, 50 so as to not distort the spring and thereby form a substantial support for the latter during the removal or replacement of the valve stem and pin.

It will be seen that the tool can be employed, in inserting the valve, by placing the valve stem 14 and spring 23 in position and then applying the tool to compress the spring whereon the pin 13 can be readily put in place, and the tool afterward removed.

What I claim is:

A valve spring lifter, comprising a lever member formed with a yoke and having an open-ended longitudinally extending slot 65 therein and formed with a plurality of notches on its underside arranged throughout the length of the slot, a spring engaging seat pivoted in the yoke, and a chain extending through the slot and adapted to 70 have any of its links engaged in the notches on the lever member to form a fulcrum for the latter.

In witness that I claim the foregoing I have hereunto subscribed my name this 10th 75 day of December 1913.

FRANK JOHNSON.
